UNITED STATES PATENT OFFICE.

JOSEPH W. HORTON, OF BLOOMFIELD, NEW JERSEY, ASSIGNOR TO WESTERN ELECTRIC COMPANY, INCORPORATED, OF NEW YORK, N. Y., A CORPORATION OF NEW YORK.

CARRIER-WAVE SIGNALING SYSTEM.

Application filed January 6, 1923. Serial No. 610,975.

This invention relates to carrier wave signaling systems and more particularly to simplified terminal equipment for such systems.

This application is a continuation in part 5 of a copending application of the present applicant, filed March 18, 1922, Serial No. 544,709, Patent No. 1,581,576.

Various types of carrier current telephone systems are now known and have been described at various times. The equipment of 10 this invention is adapted to cooperate with those systems. Reference is therefore made to an article by Messrs. Colpitts and Blackwell entitled "Carrier current telephony and 15 telegraphy" which is published in the Transactions of the American Institute of Electrical Engineers Volume XL, 1921, describing some of those systems. The equipment of this invention is also adapted to cooperate 20 with modifications of those systems, especially a modification in which different carrier frequencies are used for transmissions in opposite directions for a given two-way channel as well as for separate channels.

25 An object of this invention is to provide a simple carrier telephone equipment by means of which both telephone transmission and call signals may be transmitted over a carrier transmission line. Another object is to provide both a cheap and light weight equipment for this purpose. Still another object is to 30 provide such an equipment which will cooperate with various types of permanent carrier wave equipment. And yet another object is the provision of a portable carrier wave terminal equipment.

According to the present invention, a circuit arrangement is provided for a cheap, light weight carrier wave telephone channel 35 in which the same electron discharge devices are made to function in a variety of ways. For telephone transmission they are used in one way; for telephone reception, in a different way; and for call signaling, in still another manner. By means of a unique switching arrangement, these same devices perform their several functions with a minimum of supervision on the part of the operator.

50 The novel features which are considered characteristic of this invention are set forth with particularity in the appended claims. The invention itself, however, both as to its organization and method of operation together with the objects and advantages there-

of, will best be understood by reference to the following description, taken in connection with the accompanying drawing in which Fig. 1 shows the preferred arrangement of the invention to meet certain requirements; and Fig. 2, the terminal switching arrangement of a carrier current system with which the arrangement of Fig. 1 may be used. Fig. 3 shows a modified arrangement suitable for a somewhat different purpose. Fig. 4 is a simplification of the system of Fig. 1 adapted to operate in a slightly different manner. Fig. 5 shows a type of band filter adapted for use with this invention, while Fig. 6 is a plug ended patching conductor used for different circuit conditions. Fig. 7 shows a typical mid-line repeater arrangement with certain switching facilities. Fig. 8 shows a method of modifying the arrangement of Fig. 1 to increase its flexibility for use at a mid-line repeater.

Referring now to Fig. 1, an oscillation generator O, a modulator-demodulator-amplifier MDA, and an amplifier-detector AD are associated with a telephone handset HS, a ringing switch RS, a transfer switch TS, and plugs P¹, P², P³, and P⁴ in such a way that either telephone modulated carrier current or call signals may be either transmitted from or received at the station shown. The oscillator O comprises an electron discharge device 5 having a cathode 6, a grid 7, and a plate 8. The grid-cathode circuit of device 5 is coupled to the plate-cathode circuit by means of transformer 9 in well known manner. The frequency of the generated oscillations is determined primarily by the inductance of the grid circuit winding of transformer 9 and variable condenser 10 connected in shunt therewith. The output circuit of the oscillator O is completed through the left hand normally open contact of relay 11 and potentiometer 12. The modulator-demodulator-amplifier MDA comprises an electron discharge device 13 having a cathode 14, a grid 15 and a plate 16. When functioning as a demodulator or amplifier, the input circuit comprises a transformer 17 and normally closed right hand back contact of relay 11. When functioning as a modulator, the input circuit comprises transformer 17, right hand front contact of relay 11, and potentiometer 12. The amplifier-detector AD comprises the electron discharge device 18 having a cathode 19, a grid 20

20, and a plate 21. The filament-cathodes 6, 14 and 19 of devices 5, 13 and 18 respectively are connected in series with each other and supplied with heating current from battery 22 through variable resistances 23 and 24. Plate current for each of devices 5, 13, and 18 is supplied by battery 25 through choke coils 26, 27 and 28 respectively.

10 The handset HS comprises a transmitter T, a receiver R, and a control switch CS. Direct current for the transmitter T is supplied by battery 22 over a circuit which may be traced from the ground side of battery 22, transmitter T, primary winding of transformer 29, choke coil 30 to the other side of battery 22. Receiver R is normally connected to the output circuit of amplifier-detector AD through the normally closed back contacts of relay 31 and transformer 32. 15 The operation of control switch CS closes an energizing circuit for relays 11, 31 and 33 for current from battery 22 which circuit may be traced from the ground side of battery 22, control switch CS, conductor 34, 20 windings of relays 11, 31 and 33 in parallel, conductor 35, to the other side of battery 22. The operation of control switch CS changes the circuits from the normal receiving condition to the transmitting condition.

25 Conductors 36 are adapted to receive current incoming to the circuit by way of plugs P¹ or P³ depending upon the position of transfer switch TS. Conductors 37 carry current outgoing from the circuit to either 30 plugs P² or P⁴ likewise depending upon the position of transfer switch TS. For telephone and call signal transmission purposes, ringing switch RS is closed in its lower position. For receiving call signals, however, 35 from a distant station, ringing switch RS is closed in its upper position in which case, the energizing winding of relay 38 is connected in series with plate battery 25 in the output circuit of amplifier-detector AD. 40 The circuit for this relay may be traced from the ground side of battery 25 through battery 25, winding of relay 38, right hand blade of ringing switch RS in its upper position, plate 21 and filament 19 of discharge device 18 back to the ground side of battery 25. By means of the middle blade of ringing switch RS in its upper position, a circuit is completed at one point for call 45 signaling device 39 through battery 40, one or the other closed positions of the middle blade of transfer switch TS and front or back contact of relay 38. At the left hand blade of ringing switch RS in its upper closed position, battery 41 in series with resistance 42 is connected across the input circuit of discharge device 18.

50 Referring now to Fig. 2, a typical terminal arrangement of a carrier wave signaling system is shown. A carrier transmission line ML adapted for the transmission of both or-

55 dinary telephone current and carrier waves is connected to an ordinary telephone line 50 through the low pass filter LF and to the carrier terminal equipment by means of the common carrier circuit 51 through high pass filter HF. The filters LF and HF are of the general type described in Campbell Patent No. 1,227,113, May 22, 1917, and are used in the manner described with reference to Fig. 15 of the article by Messrs. Colpitts and Blackwell supra. Connected to the carrier circuit 51 are two two-way channels. Channel No. 1 comprises a sending branch SB Ch¹ and a receiving branch RB Ch¹. Channel No. 2 comprises a sending branch SB Ch² and a receiving branch RB Ch². Each of these branches includes a band filter, two only of which are illustrated, namely, the sending band filter SBF of channel No. 1 and the receiving band filter RBF of the same channel. These filters are of the general type disclosed in the Campbell Patent hereinbefore mentioned, and the arrangement of capacitative and inductive elements shown in Fig. 5 may be used. These filters are adapted to pass a band of frequencies individual to the branch with which the filter is used. Associated with conductors 52 and 54 is permanent carrier current terminal apparatus such as is described in the Colpitts and Blackwell paper supra. Similar apparatus is likewise associated with conductors 53 and 55. Two terminal channels only are shown in Fig. 2 but it is understood that additional channels may be associated in the same manner.

60 For use with other apparatus in a manner herein to be described, jacks J¹ are included in the carrier circuit 51, jacks J² and J⁴ in the sending branch SB Ch¹ of channel No. 1 and jacks J³ and J⁵ in the receiving branch RB Ch¹ of channel No. 1. Jacks similar to J² to J⁵ inclusive are included in the sending and receiving branches of channel No. 2.

65 One method of signaling over the carrier transmission line ML by means of the carrier terminal equipment of Fig. 1 located at each end of the line will now be described.

70 Assume that this is the only carrier transmission channel to be operated at a given time over the line ML; therefore, there will be no need for selective separation of several carrier currents at the terminal stations. Terminal equipment of Fig. 1 will be connected to the carrier line ML by the insertion of plugs P¹ in jacks J¹. Transfer switch TS will be thrown to its left hand closed position as shown in Fig. 1. The insertion of plugs P¹ in jacks J¹ disconnects the carrier terminal equipment below jacks J¹ from the carrier circuit 51 at the open contacts of jacks J¹ (normally closed).

75 In order to transmit a call signal from one station to the other, the control switch CS at the calling station is actuated. This

causes the energization of relays 11, 31 and 33 over the circuit hereinbefore traced. The output circuit of oscillator O will be completed at the left hand closed front contact (normally open) of relay 11 whereupon oscillations will be generated. These will be supplied to the input circuit of modulator-demodulator-amplifier MDA by means of potentiometer 12 and right hand closed front contact (normally open) of relay 11. The modulator-demodulator-amplifier MDA acting as an amplifier will impress the amplified oscillations upon the input circuit of amplifier-detector AD. The ringing switch RS, being in its lower closed position, connects the resistance 42 through its left hand blade directly across this input circuit and thereby provides a resistance coupling between devices 13 and 18. The amplified oscillations from amplifier-detector AD are transmitted through transformer 32, front closed contacts (normally open) of relay 31, conductors 43, conductors 36, plugs P¹, jacks J¹, carrier circuit 51, high pass filter HF 25 to the carrier transmission line ML. No current will flow in conductors 37 because, under the assumed circuit conditions, plugs P² are unconnected. Under other conditions, hereinafter to be described, such as in 30 multiplex operation, these plugs are required. The transmitter T is connected to the input circuit of modulator-demodulator-amplifier MDA through transformer 29, potentiometer 44, closed front contacts (normally open) of relay 33 and transformer 17. No use is made of this connection, however, 35 for the call signal transmitting purposes now being described. Thus carrier current is transmitted over the carrier line ML as long as the control switch CS is actuated.

The reception of call signals at the distant station will now be described in connection with the circuits of Figs. 1 and 2 connected as just described by the insertion of plugs P¹ in jacks J¹. The circuit arrangement will be identical with that just described, except that the ringing switch RS will be closed in its upper position and the control switch CS will not be actuated. Under these conditions, relays 11, 31, and 33 will be deenergized and the oscillator O will be quiescent due to the fact that its output circuit is open at the left hand contact of relay 11. The potentiometer 12 is disconnected from the input circuit of modulator-demodulator-amplifier MDA at the right hand front contact (now open) of relay 11 and a short circuit is substituted therefor at the back contact (now closed) 40 of relay 11. Current incoming from the carrier line ML flows through high pass filter HF, carrier circuit 51, jacks J¹, plugs P¹, left hand closed contact of transfer switch TS, conductors 36, back contacts of relay 33, transformer 17 to the input circuit 45 of device 13. This device 13 acting as an amplifier impresses current upon the amplifier-detector AD which acts as a detector due to the negative polarizing battery 41 impressed upon the grid 20 by way of the left hand blade of ringing switch RS in its upper closed position. The device 18 causes the energization of relay 38 which in turn closes the energizing circuit of calling device 39 at the front closed contact (normally open) of relay 38. The operator at this station will respond by throwing his ringing switch RS to its lower closed position, closing his control switch CS and speaking into his transmitter T. The calling operator will listen at his receiver at intervals during the ringing operation and will therefore, hear the called operator when he answers.

The course of a telephone message will 50 now be followed. At the sending end, control switch CS will be actuated. The operator will talk into his transmitter T which will cause voice frequency current to flow through transformer 29, potentiometer 44, closed front contacts (normally open) of relay 33, transformer 17 to the input circuit of modulator-demodulator-amplifier MDA through the right hand front contact (normally open) of relay 11 and potentiometer 12. The device 13 functioning as a modulator will transmit carrier waves, modulated in accordance with voice frequency waves over the same circuit as traced for 55 call signal carrier waves to the carrier line 60 ML.

These waves incoming from the carrier line ML at the receiving station will be impressed upon the modulator-demodulator-amplifier MDA in the same manner as were 65 the calling carrier waves previously described and will be demodulated by device 13 acting as a demodulator. For receiving speech, switch RS will be closed in its lowermost position. The voice frequency component in the output circuit of the modulator-demodulator-amplifier MDA will be amplified in the amplifier-detector AD acting as an amplifier and impressed upon the receiver R through the transformer 32 and 70 the closed back contacts of relay 31. For transmission in the opposite direction, the 75 position of the control switches CS at the two stations will be reversed.

The direction of flow of both the call signal carrier waves and the voice modulated carrier waves under the circuit conditions just described are shown by the dotted arrows. 80

Another method will now be described. For this purpose assume that it is desired to communicate over one channel of a multiplex carrier wave signaling system by employing frequencies which are not normally 85 employed in that system. Terminal equipment 90

ment corresponding to Fig. 1 will be used at each end of the carrier line ML. If the same carrier frequencies are used for transmission in both directions, band filter such as shown in Fig. 5 may be used. The plugs P¹ would be withdrawn from jacks J¹ and inserted instead in jacks J⁶ of filter BF. The other terminals of filter BF would be connected to the carrier circuit 51 by means of the patching cord PC of Fig. 6. Plugs P⁹ would be inserted in jacks J⁷ and plugs P¹⁰ in jacks J². The frequency of oscillator O would be so adjusted that the carrier wave frequency with its modulated side band frequencies would lie within the range of band filter BF or looking at the matter in another way, the constants of band filter BF would be so chosen as to transmit the carrier frequency of oscillator O together with its voice modulated side band or bands. The operation of the call signal and voice transmissions would be identical with that previously described.

Assuming still another condition, it might be desirable to employ one of the channels such as channel 1 of Fig. 2 for transmission by means of the arrangement of Fig. 1. In this assumed case, the sending band filter SBF and the receiving band filter RBF of the terminal equipment of Fig. 2 would be employed to effect frequency selection. In this case, plugs P¹ would be inserted in jacks J⁵ and plugs P² in jacks J⁴. In this case, it is assumed that different frequencies would be used for transmissions in opposite directions and the sending band filter SBF at one station would pass the same range of frequencies as the receiving band filter RBF at the other station; while the receiving band filter RBF at the first station would pass a different range of frequencies, although the same range as would be passed by the sending band filter at the other station. The frequencies of the generated carrier oscillations would be adjusted to correspond to the ranges of frequencies to be employed.

The path of the carrier waves under these circuit conditions, will now be traced from the sending to the receiving station. The control switch CS at the sending station will be actuated. Carrier waves from the oscillator O will traverse the modulator-demodulator-amplifier MDA, the amplifier-detector AD, transformer 32, closed front contacts (normally open) of relay 31, conductors 37, left hand closed contacts of the right hand pair of blades of transfer switch TS, plugs P², jacks J⁴, sending band filter SBF, normally closed contacts of jacks J², the end sections of the other channel band filters, normally closed contacts of jacks J¹, carrier circuit 51, high pass filter HF to the carrier transmission line ML. Carrier waves incoming from the carrier

line ML will traverse much the same circuit entering receiving branch RB Ch¹ through receiving band filter RBF, jacks J⁵, plugs P¹, left hand blades of transfer switch TS in the left hand closed position, closed back contacts of relay 33, transformer 17, to the input circuit of modulator-demodulator-amplifier MDA. From that point on, the circuit for call signaling or voice transmission will be the same as has been hereinbefore described.

In some cases, it may be found desirable to carry on carrier wave signaling over one carrier transmission line ML as just described and at the same time to carry on carrier wave signaling over a second carrier transmission line similar to ML in cooperation with a permanently installed carrier terminal station at the distant end of the second line. The arrangement of the permanently installed distant station may be the same as that shown in Fig. 42 of the Colpitts and Blackwell article hereinbefore mentioned. For communication with such permanently installed terminal station terminal plugs P³ would be inserted in jacks J⁵ and plugs P⁴ in jacks J⁴. The band filters SBF and RBF of Fig. 2 would be designed to cooperate with the corresponding band filters of the permanently installed equipment at the distant station. The transfer switch TS would be closed in its right hand position.

As described in the Colpitts and Blackwell article referred to hereinbefore, call signaling is effected by interrupting the flow of carrier waves which are normally present on the carrier transmission line in that system. The call signaling equipment of Fig. 1 is adapted to cooperate with such a system with the transfer switch TS in its right hand closed position. With carrier waves continuously incoming, and ringing switch RS in its upper closed position, relay 38 would be continuously energized. The energizing circuit of calling device 39 would thus be normally kept open at the back contact of relay 38. An interruption of the flow of carrier waves for call signaling would allow the armature of relay 38 to fall back and the calling device 39 would be actuated over a circuit which may be traced from battery 40, right hand closed position of the center blade of transfer switch TS, closed back contact of relay 38, center blade of ringing switch RS in its upper closed position and calling device 39 back to the other side of battery 40.

Voice transmission would be the same as that previously described in connection with the circuit arrangement first assumed.

It is thus seen that the circuit arrangement of Fig. 1 permits of a variety of functions being performed by that equipment. Due to the fact that the same devices are used for a

variety of purposes, this arrangement permits of the use of comparatively cheap and light weight equipment. This equipment has been tried out in practice and found to work satisfactorily.

A somewhat different type of equipment for accomplishing somewhat the same purpose is shown in Fig. 3. This arrangement is intended for use in connection with carrier systems employing different frequencies for transmissions in opposite directions and in which the unmodulated waves of carrier frequency are suppressed at the sending station, only the modulated components of the carrier waves being transmitted to the distant station. The arrangement of Fig. 3 can also be used with the terminal arrangement of Fig. 2 in the several ways discussed in connection with the arrangement of Fig. 1.

A balanced arrangement of electron discharge devices similar to that of Scriven Patent No. 1,396,786, November 15, 1921, is employed in the arrangement of Fig. 3. Two electron discharge devices 75 and 76 have their filaments directly connected together and heated by current from battery 77. The plate circuits are supplied in parallel with current from battery 78 through choke coils 79 and 80. Alternating current energy from the output circuit is fed back to the input circuit through conductors 81 or 82 by means of transformer 83 or 84 depending upon whether the circuit is arranged for reception or transmission by means of control switch CS. Any one or several condensers may be connected in parallel with the plate circuit winding of transformers 83 or 84 by means of switches 85 and 86 for determining the frequency of the oscillations to be generated by devices 75 and 76 with their associated circuits. As clearly explained in the Scriven patent hereinbefore noted, the unmodulated generated oscillations are not impressed upon the output conductors 87 by means of transformer 88.

If it is desired to use the arrangement of Fig. 3 with the carrier transmission line ML of Fig. 2 and only a single carrier signaling channel is desired, plugs P⁷ of Fig. 3 may be inserted in jacks J¹ of Fig. 2. In order to employ the arrangement of Fig. 3 for sending purposes, the control switch CS would be actuated. An energizing circuit for relays 89 and 90 would thereupon be completed, the circuit of which may be traced from battery 91, winding of relay 89, conductor 92, winding of relay 90, conductor 93, control switch CS back to the other side of battery 91. The energizing of relay 89 would cause energy from the output circuits of devices 75 and 76 to be fed back to the input circuits of these devices through transformer 84 over the closed front contact of relay 89. Speech frequency currents from transmitter T, flowing through low pass filter

LPT and input transformer 94, would be differentially impressed upon the input circuit of devices 75 and 76, by means of which devices, the speech modulated component of the carrier frequency would be impressed upon conductors 87 by means of output transformer 88. This current would flow by way of plugs P⁷ and jacks J¹ to the carrier transmission line ML. The low pass filter LPR prevents this modulated component of the carrier frequency from being impressed upon the receiver R and uselessly wasted.

At the distant station, an arrangement identical with Fig. 3 would be connected to the carrier transmission line ML and for reception purposes, the control switch CS would be in its open position as shown. Under these conditions, speech modulated energy incoming from the carrier transmission line ML by way of jacks J¹ and plugs P⁷ would be impressed upon conductors 95 at the closed back contacts of relay 90. It will be noted that both relays 90 and 89 are deenergized for reception purposes. The speech modulated energy in conductors 95 is differentially impressed upon devices 75 and 76 by means of transformer 94 and the de-modulated voice frequencies are impressed upon conductors 87 by means of transformer 88. This current passes through low pass filter LPR and actuates the receiver R. These currents are prevented from passing into the carrier transmission line ML by means of high pass filter HF of Fig. 2. The speech modulated energy in conductors 95 is prevented from being wasted in the transmitter T by means of the low pass filter LPT.

For transmission in a given direction, it is understood of course that the frequencies employed by both the transmitting and receiving stations are identical. Different frequencies may be employed for transmissions in opposite directions on the same channel as well as in the same or opposite directions on different channels.

If it is desired to use the arrangement of Fig. 3 at the same time that other channels of Fig. 2 are being used plugs P⁵ and P⁶ may be employed. Plugs P⁵ and P⁶ correspond respectively to plugs P¹ and P² or P³ and P⁴ of Fig. 1 and for telephone transmission may be used to perform the same functions as the corresponding plugs of Fig. 1.

The arrangement of Fig. 4 is a simplification of that of Fig. 1, only a single plug P⁸ being provided. By means of plug P⁸, much the same functions are performed by the arrangement of Fig. 4 as were performed by the arrangement of Fig. 1 as hereinbefore described when plug P¹ is used alone. For telephone communications, the operation of the circuit of Fig. 4 is identical with that of Fig. 1. The call signaling equipment is entirely different however, and due to this

difference, a transformer 100 is employed to couple the output circuit of device 13 to the input circuit of device 18.

The modulator-demodulator MD of Fig. 4 is very similar to the modulator-demodulator-amplifier MDA of Fig. 1, except that it does not function at any time solely as an amplifier. The amplifier A of Fig. 4 is much like the amplifier-detector AD, when 10 the latter is functioning solely as an amplifier.

For call signaling, switch 101 is provided. When this switch is thrown to its left hand position, relay 11 is energized independently 15 of control switch CS over a circuit which may be traced from the ground side of battery 22 through battery 22, conductor 35, winding of relay 11 to ground at switch 101. Under these conditions, the oscillator O produces 20 carrier waves in the same manner as they are produced for telephone transmission by the closure of control switch CS. These oscillations are impressed upon the modulator-demodulator MD but not upon 25 the carrier transmission line ML by way of plugs P⁸, since relay 31 is deenergized. A distant station similar to that of Fig. 4 may call the station of Fig. 4 by impressing carrier waves upon the carrier transmission line 30 ML by means of control switch CS. These waves incoming at the local station by way of plugs P⁸ are also impressed upon the input circuit of modulator-demodulator MD by means of transformer 17. If the locally 35 generated carrier waves and the incoming carrier waves differ from one another by an audible frequency, they will combine in the modulator-demodulator MD, producing an audible frequency component in the output 40 circuit thereof. This audible frequency component will be impressed upon the receiver R by way of transformer 100, amplifier A, transformer 32 and closed back contacts of relay 31. The tone in the receiver produced thereby may be of sufficient volume 45 to serve as a call signal and take the place of the calling device 39 of Fig. 1.

Referring now to Fig. 7 a circuit arrangement for a midline repeater is there shown. 50 This repeater is similar to the repeater shown in Fig. 24 of the Colpitts and Blackwell article supra. Filters HF¹ and LF¹ associated with line ML¹, and HF² and LF² associated with line ML² serve the same purpose 55 at the repeater as the respective filters HF and LF of Fig. 2 serve at a terminal station. They serve to separate the ordinary telephone transmissions from the carrier wave transmissions. Filters HGF¹ and HGF² in one branch and filters LGF¹ and LGF² in the other branch of the two-way 60 repeater having repeater elements RE and RW function in well-known manner. The high group of carrier frequencies are amplified by repeater element RE, while the lower 65

group is amplified by repeater element RW. The arrows show the directions of the transmissions.

Jacks J¹⁰ to J¹⁷, inclusive, furnish a ready means of making connections with various parts of the circuit as will be explained more in detail hereinafter.

In Fig. 8 is shown a method of modifying the arrangement of Fig. 1 to increase the flexibility of that system. A reversing switch 109 is inserted between the contacts of relay 38 and battery 40. The switch arm 110 is made detachable from the rod of transfer switch TS by means of a removable pin 108. An additional switch arm 107 is provided whereby the frequency of the oscillator O may be automatically determined by the position of transfer switch TS. The position of switch arm 107 determines which one of condensers 105 and 106 is connected into the frequency determining circuit of oscillator O.

The relationship of the other parts of the circuit is clear from the reference characters since the same reference characters in all of the figures designate the same respective elements.

Should it be desired to connect the equipment of Fig. 8 to the equipment of Fig. 7 in such a manner that communication could be had over either of the outgoing lines ML¹ or ML² plugs P¹ and P² might be inserted in jacks J¹⁰ and J¹⁴, respectively, and plugs P³ and P⁴ in jacks J¹⁷, and J¹³, respectively. With the plugs P¹ and P² so arranged for communication with a station at the distant end of line ML¹ and the transfer switch thrown to the left (the position shown), a carrier frequency in the lower group must be used. Therefore, condenser 105 must be of 105 larger capacity than condenser 106 which is connected into the circuit when transfer switch TS is thrown to the right for communication over line ML² by way of plugs P³ and P⁴.

If it is desired to communicate over the line ML¹ through repeater elements RE and RW, plugs P¹ and P² would be inserted in jacks J¹² and J¹⁶. Instead of this combination, it may be desired to make use of these repeater elements when communicating over line ML², in which case, plugs P³ and P⁴ would be inserted in jacks J¹⁵ and J¹¹, respectively.

The arrangement of Fig. 8 also provides a flexible system for ringing over lines ML¹ and ML². First assume that plugs P¹ and P² are inserted in jacks J¹⁰ and J¹⁴, respectively, and plugs P³ and P⁴ in jacks J¹⁷ and J¹³, respectively. With the reversing switch 109 thrown downward the system is set to receive call signals from a terminal station which suppresses the carrier waves during the signaling interval provided the transfer switch TS is thrown to the left. Call sig-

nals may be received from a terminal which transmits the carrier waves during the signaling interval provided the transfer switch TS is thrown to the right. Thus, the arrangement described would function if the terminal station at the distant end of line ML¹ were adapted to suppress the carrier wave during the call signaling interval and the terminal station at the distant end of line ML² were adapted to transmit the carrier waves during the call signaling interval.

In order that the system may be used to receive call signals from both directions from terminal stations both of which suppress the carrier waves during the call signaling interval, pin 108 may be withdrawn so that the switch arm 110 may remain thrown to the left regardless of the position of transverse switch TS. To receive call signals from both directions from terminal stations both of which transmit the carrier waves during the signaling interval, the reversing switch 109 may be thrown upward.

Other possible combinations of these switches for different call signaling conditions are shown in the following table:

Condition of carrier waves at distant station for call signaling		Condition of switch arm 110	Position of switch arm TS	Position of reversing switch 109
Line ML ¹	Line ML ²			
Suppressed.	Suppressed.	Unconnected.	Left.	Down.
Suppressed.	Suppressed.	Unconnected.	Right.	Up.
Transmitted.	Transmitted.	Unconnected.	Left.	Up.
Transmitted.	Transmitted.	Unconnected.	Right.	Down.
Suppressed.	Transmitted.	Connected.	Left-right.	Down.
Transmitted.	Suppressed.	Connected.	Left-right.	Up.

The repeater elements RE and RW are preferably electron discharge amplifying elements such as are described in connection with Figs. 21 and 22 of the Colpitts and Blackwell article supra.

Other methods of operating these circuits will no doubt be apparent to those skilled in the art and any such use in combinations, as defined by the appended claims, is to be understood to come within the scope of this invention.

What is claimed is:

1. A carrier telephone terminal apparatus comprising an electron discharge device adapted to produce oscillations, a second electron discharge device adapted to receive modulated carrier oscillations and to translate said oscillations into signals, a microphone, and switching means for causing the first device to produce oscillations and to impress them upon the second device, to adapt said microphone to also impress signals on said second device, and to connect the output of said second device to a carrier transmission line.

2. A carrier current terminal equipment comprising a first electron discharge device for producing oscillations, a second electron

discharge device adapted to function as a modulator, a detector, or an amplifier, a third electron discharge device adapted to function either as an amplifier or a detector, a telephone transmitter, a telephone receiver, a call signal device, a carrier wave conductor, means to associate said second and third devices and said call signal device to receive call signals from the carrier wave conductor, other means to associate said first, second and third devices with each other and with said telephone transmitter to transmit either call or telephone signals, and still other means to associate said second and third devices and said telephone receiver to receive telephone signals.

3. A carrier telephone terminal equipment comprising a first electron discharge device for producing oscillations, a second electron discharge device adapted to function as a modulator, a detector, or an amplifier, a third electron discharge device adapted to function either as an amplifier or detector, a carrier wave conductor, means to associate said second and third devices with said carrier wave conductor for the reception of call signals, means to associate said first, second and third devices with said carrier wave conductors for the transmission of either call or telephone signals, and other means to associate said second and third devices for the reception of telephone signals.

4. In a carrier current terminal equipment, a normally inactive oscillator, a device normally functioning as a demodulator, a second device normally functioning as an amplifier, a telephone hand-set comprising a telephone transmitter, a telephone receiver and a push button switch, and means under the control of said switch for causing said oscillator to generate oscillations and to cause said modulator to function as an amplifier to transmit the generated oscillations to said second device.

5. In a carrier wave signaling system, a carrier terminal equipment, carrier current conductors, a telephone transmitter, a telephone receiver, an electron discharge oscillator, an electron discharge modulator-demodulator, an electron discharge amplifier, a relay adapted when energized to close the output circuit of said oscillator and to connect said oscillator to said modulator-demodulator and when deenergized to open the output circuit of said oscillator and to connect a short-circuit in place of the oscillator output connection to said modulator-demodulator, a second relay adapted when energized to connect said transmitter to the input circuit of said modulator-demodulator and when deenergized to connect said carrier current conductors to said input circuit, a third relay adapted when energized to connect said carrier current conductors to the output circuit of said amplifier and when

- deenergized to connect said receiver to said output circuit, and means to cause the energization and deenergization of said relays.
6. In a carrier current telephone equipment, carrier current conductors, a plurality of electron discharge devices and associated circuits adapted for transmitting and receiving signals by means of carrier currents, a plurality of relays adapted when energized to connect said devices and circuit to said carrier current conductors for transmitting telephone signals over said conductors and when deenergized to connect said devices and circuits to said carrier current conductors for receiving telephone signals therefrom, and switching means for causing the energization and deenergization of said relays.
7. In a carrier current terminal equipment, a normally inactive oscillator, a device normally functioning as a demodulator, a telephone hand set comprising a telephone transmitter, a telephone receiver and a push button switch, means under the control of said switch for causing said oscillator to generate oscillations and to cause said demodulator to function as a modulator, and means independent of said switch to cause said oscillator to generate oscillations and to transmit said generated oscillations to said modulator.
8. In a signaling system, a transmission circuit for transmitting and receiving, a source of waves to be transmitted, a receiving circuit, a space discharge device having a cathode, an anode and a grid or control element, switching means for connecting said space discharge device between said source and said transmission circuit so as to amplify the waves from said source and impress them upon said circuit for transmission, and circuits controlled by said switching means when in another position to convert said device into a detector of incoming waves, said switching device in going to said last mentioned position acting to shift the output connections of said device to connect to said receiving circuit and at the same time acting to connect a grid polarizing means between the grid and cathode of said device to bias the grid negative with respect to the cathode whereby said device is made effective as a detector.
9. In a carrier telephone terminal system comprising a transmitting circuit, a receiving circuit, and a plurality of space discharge devices, means for connecting said devices in operative relationship with said transmitting circuit, and means for disconnecting said devices from said transmitting circuit and causing them to cooperate with said receiving circuit.
10. A carrier telephone terminal apparatus comprising a source of carrier waves, a source of low frequency signal waves, a space discharge modulator for modulating said carrier waves in accordance with said low frequency waves, a space discharge amplifier, a transmitting circuit, and means for connecting said modulator and amplifier in said circuit, a receiving circuit, and means for disconnecting said modulator and amplifier from said transmitting circuit and connecting them in said receiving circuit in such manner that they are caused to operate as an amplifier and detector, respectively, of received waves.

In witness whereof, I hereunto subscribe my name this 4th day of January, A. D., 1923.

JOSEPH W. HORTON.
